UNITED STATES PATENT OFFICE.

FRED E. WEIGEL, OF LEOMINSTER, MASSACHUSETTS, ASSIGNOR TO J. C. DOWD & CO.,
OF NEW YORK, N. Y., A CORPORATION OF NEW YORK.

DESIGN FOR A RACK FOR MANICURING SET.

Application filed April 9, 1926. Serial No. 17,235. Term of patent 3½ years.

To all whom it may concern:

Be it known that I, FRED E. WEIGEL, a citizen of the United States, residing at Leominster, in the county of Worcester and State of Massachusetts, have invented a new, original, and ornamental Design for Rack for Manicuring Set, of which the following is a specification, reference being had to the accompanying drawing, forming part thereof.

The figure is a perspective view showing my new design.

I claim:

The ornamental design for a rack for manicuring set as shown.

FRED E. WEIGEL.
